UNITED STATES PATENT OFFICE.

ALFRED W. FRENCH, OF PIQUA, OHIO.

PRESS-PLATE.

1,256,676.

Specification of Letters Patent. Patented Feb. 19, 1918.

Application filed April 28, 1915. Serial No. 24,512.

To all whom it may concern:

Be it known that I, ALFRED W. FRENCH, a citizen of the United States, residing at Piqua, in the county of Miami and State of Ohio, have invented a new and useful Improvement in Press-Plates, of which the following is a specification.

This invention relates to press plates of the kind which are used in presses for expressing oil bearing meal or material, and between which the previously formed cakes of meal are placed.

Cotton seed meal has been found to have a much greater tendency to creep or spread laterally when compressed between plates in this way than linseed meal, and the plates employed in most types of cotton seed presses for operating on previously formed cakes have heretofore been constructed so as to provide substantially box-like structures which telescope so that the walls thereof prevent the cake from spreading while being compressed. It has been found that by providing ample drainage means for the oil at short intervals on the surface of the press plates, the tendency of the meal to creep is greatly decreased, so that by constructing the plates as hereinafter described plates occupying less space in the press can be used, thereby considerably increasing the capacity of the press. The plates thus formed can also be used to advantage on linseed presses so that a press equipped with these plates is adapted for use either for cotton seed or linseed meal.

The objects of this invention are to produce a press plate of this kind which is so constructed as to enable the oil to drain quickly from all parts of the cake but is nevertheless of materially less thickness than the plates heretofore used, and which can be used either for expressing cotton seed or linseed oil; also to provide plates of this kind with compression strips of improved construction which are arranged at the edge portions of the plates on the opposite faces thereof to confine the edge portions of the cake and resist the spreading thereof and to facilitate the placing of the cake in proper position between the press plates; also to provide the press plate with a surface of

such character as to cause the press cloth to cling or adhere to the plate without damaging the texture of the cloth and to prevent the cloth from being strained or broken by the spreading of the oil bearing material under pressure; also to improve the construction of apparatus of this kind in the respects hereinafter mentioned.

In the accompanying drawings:

Figure 1 is a top plan view of a press plate embodying the invention, with the mat plate partly broken away to show the lower or supporting plate.

Fig. 2 is a side elevation thereof.

Fig. 3 is a fragmentary front elevation of two press plates showing the same in the positions which they occupy relatively to each other before compressing the cakes.

Fig. 4 is a similar view showing two plates in the position which they occupy after the cakes have been compressed.

Fig. 5 is a fragmentary sectional elevation of a press plate on line 5-5, Fig. 1, on an enlarged scale.

Fig. 6 is a fragmentary bottom plan view of the mat plate.

Fig. 7 is a fragmentary sectional elevation of a press plate on a full-sized scale, on line 7-7, Fig. 8.

Fig. 8 is a fragmentary plan view thereof on the same scale as Fig. 7, showing the surface grooving of the plates.

Fig. 9 is a transverse sectional elevation of two press plates provided with compression strips of modified construction.

Fig. 10 is a fragmentary transverse sectional elevation of two press plates provided with compression strips of another modified form.

The press plate comprises a main or supporting plate A and a smaller plate or mat B secured on the face thereof. In the construction shown, the mat B is secured to the upper face of the main plate by suitable means, such as screws or the like a. The main plate A is provided with the usual notched portions a' a'' near the front and rear corners thereof for the usual links (not shown) which connect adjacent plates, or the plate can be provided with any other suitable means for connection with adjacent

plates. The main plate A is provided in its upper face with a plurality of grooves C extending longitudinally of the plate, and the lower face of the mat B is provided with 5 corresponding grooves D adapted to register with the grooves C in the main plate to form longitudinal conduits or channels for the drainage of the oil. The oil enters the channels through a plurality of small perforations *d* in the upper plate, the perforations being preferably enlarged below the upper end portions thereof to enable them to be more readily cleared of fine particles of meal entering therein with the oil and prevent 10 the meal from collecting in and clogging the perforations. A large number of these perforations are distributed over the surface of the upper plate at short intervals so as to afford a rapid draining of the oil 15 from the cake and thereby prevent the spreading of the sides of the cake. The facilities for rapidly draining the oil from the cake makes it possible to dispense with the side walls usually employed in connection 20 with cotton seed presses, so that the amount of vertical space occupied by one of these plates is greatly reduced, thus increasing the capacity of the press.

The press plates are provided at opposite sides with compression or cake retaining strips or dams which serve to resist the spreading of the side edge portions of the cake and thus prevent the forming of soft or insufficiently compressed parts at the 25 edges of the cake. In the construction shown for this purpose, compression strips E are secured on the upper sides of the press plates and corresponding strips F are secured to the undersides of the plates. The 30 compression strips may be secured to the plates in any suitable manner, for example by means of rivets *e* and *f*. The upper compression strips E are preferably, as shown, riveted on the mat B while the lower 35 strips are separately riveted onto the main plate, and the compression strips are preferably so made as to telescope or lie one partly within the other when adjacent plates are close together. For this purpose 40 the strip E, as shown in Figs. 3 and 4, is provided with an upwardly extending lip *e'* adapted to extend up beside the beveled inner edge *f'* on the adjacent strip F when the plates are close together, as shown in 45 Fig. 4.

An alternative construction for accomplishing the same result is shown in Fig. 9, in which compression strips E' and F' are secured respectively to the upper and 50 lower faces of the plate. One flange or leg of an angle bar G is secured between each strip E' and the mat B, and the other flange extends upwardly forming a dam

or wall to prevent the spreading of the meal in the cake toward the side of the 55 plate.

In either of the constructions shown, the upper compression strips of each plate serve also to guide the cake when the pressman places the cake into the press by means of 70 the usual cake pan, since the strips co-operate with the cake pan to guide the same in its movement lengthwise of the plate, so that the cake of oil bearing material can be of the full width of the space between 75 the compression strips. This insures a uniform compression of the cake and prevents the spreading of the edges of the cake.

The compression strips E² and F², shown in Fig. 10, are of a form which do not overlap or telescope as in the case of other strips described. Press plates equipped with strips such as shown in Fig. 10 are intended more particularly for pressing linseed oil and for use with wide press cloths which 85 project out between the compression strips, as shown. With the exception of the construction of the compression strips, the press plates shown in Figs. 9 and 10 are preferably of the same construction as those 90 shown in the other figures and above described.

It is desirable to provide the press plates with surfaces which will prevent the press cloths in which the meal cakes are wrapped 95 from being spread laterally by the lateral spreading or flow of the meal under pressure and being thereby strained or broken. For this purpose the upper and lower surfaces of the press plates are provided with 100 a large number of relatively narrow shallow grooves or furrows I, which, in the construction shown, extend longitudinally and transversely of the plates. The grooves are preferably arranged in parallel groups or 105 series, each consisting of a plurality of parallel grooves, thus leaving squares of ungrooved or plane surface between the intersecting groups or series of grooves. At the intersection of the groups of grooves, 110 a number of small pyramids or projections are formed which are not large enough to penetrate the press cloth sufficiently to break or injure the same. The oily meal which is pressed through the interstices of the 115 cloth becomes packed into the grooves and the crevices between the surface projections of the press plates and forms a more or less sticky surface to which the press cloth clings or adheres and which prevents the 120 creeping and stretching of the cloth. A suitable size for the surface grooves is about one-sixteenth of an inch between centers. The parts of the smooth surface of the 125 plates prevent the press cloth from adhering too tightly to the plates. The packed meal

in the crevices also assists in preventing the surface projections from entering the meshes of the cloth deep enough to injure the cloth. The holes *d* leading to the draining channels 5 preferably terminate in the bottoms of the grooves to facilitate draining of the oil. In the manufacture of the press plates, the cloth-engaging surface thereof can be formed by cutting the grooves in the smooth 10 surfaces of the plates by a suitable cutting tool or in any other suitable way.

Press plates of the kind described can be economically manufactured since they are made of two flat plates, preferably of steel, 15 and of about like thickness, and compression strips which can also be economically made are secured thereto. The press plates described, formed of the comparatively thin main and mat plates, occupy very much less 20 space than those ordinarily used in cotton seed presses, so that by the use of these plates a greater number of plates can be used in a press and the capacity of the press is thus very materially increased. The 25 plates nevertheless afford ample drainage facilities for the ready escape of the oil throughout the area of the cake. By making the plates of steel they can easily be straightened if they become bent, owing to 30 the operator neglecting to insert a cake between two adjacent plates. By constructing the compression strips so that they will telescope or nest together when the plates are close together, more complete obstruc- 35 tion is offered to the lateral spreading of the cake when under pressure, than would be offered if the compression strips were merely provided with flat abutting faces.

While it is preferred to employ press 40 plates embodying all the features described, yet it will be understood that the invention is not necessarily limited to all of the features of the construction of the plates shown, since the compression strips or the surface 45 grooving could be used on press plates of other construction, while the press plates having internal oil grooves formed as described could be used without the compression strips and the surface grooving de- 50 scribed.

I claim as my invention:

1. A press plate consisting of two flat plates arranged face to face, each of said plates being provided with grooves arranged 55 so that the grooves of one plate register with the grooves of the other plate and form oil draining channels, the upper of said plates having perforations through the same communicating with said channels.

60 2. The combination of a plate having oil draining grooves in its upper surface, a second plate of about equal thickness with the first plate mounted on said upper surface

and having oil draining grooves in its lower surface registering with the grooves in said 65 first mentioned plate and forming therewith oil draining channels, said second plate having perforations therethrough communicating with said oil channels.

3. A press plate for oil presses having a 70 multiplicity of narrow shallow grooves in its surface, said grooves being adapted to retain small quantities of oil meal to form a surface to which the press cloth adheres.

4. A press plate for oil presses having a 75 multiplicity of narrow shallow intersecting surface grooves with relatively abrupt walls adapted to retain therein oil meal to form a surface to which the press cloth adheres. 80

5. A press plate for oil presses having a 85 multiplicity of narrow shallow surface grooves arranged in spaced intersecting groups and having ungrooved surface portions between said groups of grooves.

6. A press plate comprising a main plate and a mat plate secured together face to face, said plates being of substantially equal thickness and provided in their contacting 90 faces with grooves which register to form oil drainage channels, and said mat plate having perforations therethrough connecting with said channels, and said main plate extending laterally beyond said mat plate.

7. A press plate comprising a main plate 95 and a mat plate secured together face to face, said plates being of substantially equal thickness and provided in their contacting faces with grooves which register to form oil drainage channels, said mat plate having 100 perforations therethrough connecting with said channels, and said main plate extending laterally beyond said mat plate, upwardly projecting strips secured on the edge portions of said mat plate, and downwardly projecting strips secured on the edge 105 portions of said main plate.

8. A press plate comprising a main plate and a mat plate secured together face to face, said plates being of substantially equal 110 thickness and provided in their contacting faces with grooves which register to form oil drainage channels, and said mat plate having perforations therethrough connecting with said channels, said press plate 115 being provided on its upper side with portions projecting upwardly along opposite edge portions of said mat plate, and with parallel downwardly projecting portions on its underside, the upwardly and downwardly projecting portions of adjacent press plates coöoperating to confine the material being pressed.

9. A press plate comprising a main plate and a mat plate secured together face to 125 face, said plates being of substantially equal

thickness and said mat plate having perforations therethrough, oil drainage channels being formed in the press plate between said contacting plates, said main plate extending laterally beyond said mat plate, and said press plate being provided on its upper side with portions projecting upwardly along opposite edge portions of said mat plate, and with parallel downwardly projecting portions on its underside,

the upwardly and downwardly projecting portions of adjacent press plates coöperating to confine the material being pressed.

Witness my hand, this 26th day of April, 1915.
